UNITED STATES PATENT OFFICE

CLYDE G. BUTLER, OF CINCINNATI, OHIO, ASSIGNOR TO THE CINCINNATI BALL CRANK COMPANY, OF CINCINNATI, OHIO, A CORPORATION OF OHIO

LUBRICANT SUPPLY PUMP

Application filed June 21, 1930. Serial No. 462,809.

This invention relates to lubricating systems and is particularly directed to a pumping unit for forcing lubricant, such as grease, from a supply container into the pipes of a system. The present pumping unit is capable of developing moderate pressures such as would be suitable for feeding the lubricant into the transmission casings, etc., and contemplates the provision of high pressure devices or guns at the discharge ends of various pipe lines extending from a main header to which the grease is supplied from the pump. The pump is designed to operate to maintain a predetermined pressure throughout the feed line or header whereby the lubricant is supplied to the points of discharge at all times.

It is, therefore, an object of the present invention to provide a lubricant pumping unit moving the lubricant from a large reservoir into feed or supply lines under a moderate degree of pressure and in a steady uniform flow.

It is another object of this invention to provide a pump of this nature which withdraws the lubricant from the reservoir and feeds the lubricant by means of a number of piston and cylinder units actuated from a common central source. This multiple piston pump by successive action of the pistons creates a constant steady discharge of lubricant from the reservoir and overcomes the disadvantages of an ordinary single piston pump which moves the lubricant in noticeable impulses or shots which, because of their intermittency, create an uneven feed. More specifically, the present object includes the provision of an improved actuating medium centrally located relative to the pistons which imparts successive strokes to the pistons and which includes an extremely novel mounting of the piston connector means about a rotating eccentric.

A further object of the invention is to provide improved passageways from the reservoir to the respective pump cylinders whereby movement of the lubricant to the cylinders is facilitated and full advantage taken of the weight of the lubricant and any pressure exerted on the body of the lubricant.

It is another object in connection with the foregoing object to provide a novel mounting of filtering screens in the respective lubricant passageways whereby the screens are firmly mounted and removable without difficulty.

Other objects relate to the general construction of the pump and drive therefore and the system installation relative to the pump, which objects along with certain other advantages will be more fully apparent from the description of the accompanying drawings in which:

Figure 1 is a top plan view of the complete unit showing the supply pipe broken off. 65

Figure 2 is a side elevation of Figure 1 illustrating the motor in phantom lines for disclosing apparatus in back of the motor.

Figure 3 is a sectional view taken on line 3—3, Figure 1, the top of the reservoir or container being broken off and the view illustrating the general construction of the pump. 70

Figure 4 is a sectional view taken on line 4—4, Figure 3, a portion at one side thereof being broken away to more fully illustrate the mounting of a filter. 75

Figure 5 is an enlarged sectional view taken on line 5—5, Figure 3, illustrating, in detail, the multiple piston and cylinder arrangement and the common central means for actuating the respective pistons. 80

Figure 6 is a fragmentary view of the central actuating means showing the eccentric in a midway or laterally disposed position wherein the respective pistons are at the same position. 85

Figure 7 is a sectional view taken on line 7—7, Figure 3, illustrating the transmission between the motor shaft and the shaft of the pump. 90

Figure 8 is a central view taken on line 8—8, Figure 7, detailing the mounting of the multiple piston actuating means on the shaft of the pump.

Generally described, the pump comprises a reservoir 10 mounted on a multiple cylinder block 11 which is hollow centrally for housing the piston actuating means. This cylinder block is mounted on a transmission casting 12 bolted to a floor or base plate 13. A 100

motor 14 for driving the transmission is bolted to the plate.

The discharge or supply conduits 15 extending from the pump are connected to a common line 16 which extends to the header into which various pressure devices are tapped (not shown). The motor is controlled automatically by means of a pressure device 17 actuated by the lubricant in the discharge line whereby the pump only operates below a certain pressure.

Referring to the drawings, the cylinder block 11 is of general circular form and as shown in Figure 8 is of hollow design, generally cylindrical on its vertical axis. Toward the upper portion thereof the walls flare outwardly to provide a horizontal attaching flange 11^a upon which the container tank or reservoir 10 is supported. The cylinder block is closed at its upper end with the exception of passageways or ports 18—18 extending independently of the main cylinder of the block from the reservoir to the respective cylinders.

The container tank is cylindrical and includes an inner ring 19 secured relative to its lower end by press-fitting or spot welding. The ring provides a counterturned portion in its outer face within which the metal of the container is disposed. The aforesaid ring is secured to the attachment flange of the cylinder block by means of bolts 20 or any suitable means and a sealing ring 21 is inserted between the respective parts. The upper end of the container is closed by means of a removable cover 22 including the conventional handle 23. Within the container a gravity actuated follower plate 24 is in sliding contact with the walls of the cylinder and is provided with a handle 25 for extraction of the same when the lubricant has been exhausted from the container.

The cylinder block includes a bearing hub 26 centrally of its upper closed end, which hub is vertically disposed for mounting the upper end of the pumping shaft 27, a bearing sleeve 28 being inserted in the hub and the upper end of the bore through the hub being closed by means of a disc 29. The lower end of the pump shaft is mounted within the transmission casing. The transmission casing 12 is bowl shaped and provided with radially extending legs 30 which are bolted to the base plate 13. A depending hub 31 is formed centrally of the bowl of the transmission casing including a bearing sleeve 32 within which sleeve the lower end of the pump shaft 27 is mounted. A worm wheel 33 is keyed to the pump shaft and rests upon a collar 34 supported upon the lower bearing hub. This worm wheel is driven by means of a worm 35 journaled in the wall of the transmission casing. The worm 35 is formed on a drive shaft 36 which extends beyond the confines of the transmission casing and carries one element 37 of a flexible coupling, the other element of

which is mounted on the stub shaft 38 of the motor 14 bolted to the base plate 13.

The worm shaft 36 at the extreme end from the motor is mounted in a lug of the transmission casing in a bearing sleeve 39. The outer end of the bore housing the sleeve 39 is closed by means of a cap plate 40 bolted to the transmission casing. An end thrust ball bearing 41 is mounted on an intermediate counter-turned portion of the shaft between the worm and the bearing sleeve and carries the thrust between the worm and bearing.

The other end of the shaft is mounted in a sleeve 42 supported within a bore in the adjacent wall of the transmission casing, the bearing and shaft being sealed by means of a packing gland nut 43 engaging a packing 44 disposed about the shaft, the nut being drawn against the outer face of the boss by means of screws.

The common means for actuating the respective pistons is mounted upon the pump shaft just above the worm wheel. The actuating means fastened to the shaft is an eccentric disc 45 which is keyed to the shaft. A pair of large washers 46 or circular plates are disposed one above and one below the eccentric disc, these washers also being keyed to the shaft. These washers are of greater diameter than the eccentric.

In the present instance a pair of pump units, each including a cylinder 47 and piston 48 is provided in diametrically opposite sides of the cylinder block. Each of these pistons is flexibly connected to the eccentric. Each connection is accomplished by means of a link 48^a, which includes a semicircular ring portion having its inner face engaged about the eccentric. These inner faces are less than 180° in circumference so that a space is left between the adjacent ends of the links surrounding the eccentric. The semicircular links providing the aforesaid faces are secured to the eccentric by means of annuli 49—49. The upper and lower outer corners of the respective semicircular rings of the links are grooved for receiving a respective annulus. Therefore, there is an annulus at the top and bottom of the joined links. These binding annuli or rings securely lash the links about the eccentric for rotation about the eccentric, and the space between the adjacent ends of the links is sufficient to permit revolution of the links when the eccentric center swings laterally from the path of movement of the respective pistons.

The outer ends of the links are bifurcated and carry blocks 50 between their respective bifurcations. These blocks are rotatively secured in position by pins 51 which are fixed within and between the arms thereof. The blocks are attached to or integral with the inner ends of the respective pistons.

The cylinders containing the respective pistons are mounted within radially extend-

ing bosses 52 of the cylinder block formed at diametrically opposite sides thereof. The passageways 18-18 extend down from the container into communication with the respective cylinders and the bosses. These passageways are circular at the extreme upper intake ends, each circular portion terminating in a shoulder 53.

A slot 54 is cut through the side wall of the cylinder block radially of each circular opening and is of a greater width than the diameter of the opening. The base of this slot coincides with the aforesaid shoulder. A filter 55 is mounted upon each ledge formed by the shoulder and the slot. Each of these filters comprises a frame 56 providing a central opening concentric with the central portion of the passageway, when in operative position, and a circular section of screen 57 mounted in a counterturned portion of the central opening of the filter frame. These filter frames have radial extensions or ribs 58 extending out through the slot, the ribs being secured to elongated plates 59 covering the outer ends of the slot openings and secured to the boss 60 which includes the slot by means of wing headed screws 61. When the filters become clogged due to long use and excessive foreign matter in the grease they are quickly removed by loosening the wing headed screws and extracting the filters through the slots.

Beneath the filters, the inner walls of the passageways incline outwardly from the center of the cylinder block for the purpose of directing the grease to the intake port of each cylinder. The cylinders are inserted into the bosses of the cylinder block from the outside and are bolted in position by means of intermediate flanges 62 formed integrally therewith.

Between the flange and the inner end of each cylinder a laterally disposed intake port 63 is provided. This intake port is constructed by transversely slotting the cylinder to the interior of the bore thereof. The upper surface of the cylinder or the surface adjacent the passageway is inclined toward the slot whereby a tapered or funnel shaped intake opening is provided for more readily introducing the grease to the interior of the cylinder. Furthermore to aid in positive feed by placing the grease entirely around the cylinder and thus making the supply uniform and steady at all points of the slot, an annular groove 64 is provided in the boss surrounding the cylinder and communicating at both ends with the passageway. Each piston in its retractive stroke moves back beyond the slot whereupon the grease immediately moves into the cylinder end, the pressure on the grease induced by the weight of the booster or follower plate as well as the suction within the cylinder aiding in feeding the grease into the cylinders. The suction in the

cylinders is created on the back stroke of the piston because of the provision of a check valve 65 mounted in the outer end of the cylinder.

A check valve unit is inserted in the end 70 of the cylinder within a counterturned bore thereof, therefore abutting a shoulder 66 marking the outer end of the actual cylinder bore. This check valve unit consists of a cylinder or sleeve 67 carrying a seat 68 at its inner end, the seat countersunk within the end of the sleeve and the end longitudinally slotted as at 69 for a short distance or beyond the seat. The valve sleeve is held down against a sealing ring by means of a flanged nut 70 screw threaded into the outer end of the counterturned bore. The pistons 48 have tips 48^b which are adapted to unseat the valves 65 through central discharge bores in the seats 68.

The valve 65 which includes a plain abutting surface covers the central bore in the seat which communicates with the cylinder and a shank 71 extending rearwardly from the body of the valve. A spring 72 under compression engages the body of the valve about the stud or shank and is seated at its outer end within a pocket in the flanged nut. The slots in the sleeve constitute an outward clearance for the grease as it passes between the valve and the valve seat and permits a greater lateral rush of grease for clearing the seat.

The features of this piston and cylinder arrangement have been claimed in a copending application Serial No. 448, 368. The discharge pipes 15 extending from the respective cylinders are attached to laterally extending bosses 73 thereof by screw threading the pipe into the bosses. The grease passes from the check valve sleeve through radial ports 74 therein communicating with an annular groove 75 surrounding the sleeve at this point, the bore of the lateral boss enters this annular groove.

The respective pipes leading from the plurality of pumping cylinders are extended to the common pipe 16 which leads to the port of discharge. Fittings 76 are provided in the respective nuts securing the valve sleeves in position for additional attaching hose lines to the pump if desired.

As shown in Figure 2, the pressure control device 17 is mounted on the base plate and is in communication with the main discharge line by way of a pipe extension 77 and a pressure gauge 78 is mounted on the pipe at this point. The pressure device contains mechanism for operating an electric switch therein, which switch is inserted in the wiring leads 79 extending to the motor in any conventional manner for causing the motor to start when a predetermined low pressure is reached in the line and to stop when a predetermined high pressure is reached. The elec-

trical connections may be plugged into any convenient socket.

Having described my invention, I claim:

- 5 1. In a device of the class described, a cylinder support, a lubricant reservoir mounted on said support, a cylinder mounted in the support, said cylinder including an intake port, said support having a passageway extending from the reservoir to the cylinder intake port, said support including a slot 10 extending laterally from the exterior into the passageway, said passageway including a shoulder formed in the same plane with the bottom of the slot and a filter adapted to be inserted through the slot to rest on the shoulder, and means for securing the filter in place. 15
- 20 2. In a device of the class described, a cylinder support, a pumping cylinder mounted in said support, a lubricant reservoir mounted on said support, a passageway extending from the reservoir to the cylinder, the wall of said passageway outwardly slotted to the exterior of the support, and a filter insertable through said slot for disposal across said 25 passageway. 30
- 30 3. In a device of the class described, a cylinder support, a cylinder mounted in the support, said cylinder including an intake port, said support having a passageway extending to the cylinder intake port, a slot extending laterally into the passageway, said passageway having a shoulder formed in the same plane with the bottom of the slot, and a filter adapted to be inserted through the slot to 35 rest on the shoulder within the passageway. 40
- 40 4. In a device of the class described, a cylinder support, a pumping cylinder mounted in said support, a lubricant reservoir mounted on said support, a passageway extending from the reservoir to the cylinder, the wall of said passageway outwardly slotted to the exterior of the support, a filter insertable through said slot for disposal in said passageway, a face plate disposed on the outer end 45 of the filter and adapted to lie across the outer end of the slot, and means for securing the plate in position across the end of the slot. 50
- 50 5. In a lubricant pump, a circular support, a cylindrical grease container mounted on said circular support, a plurality of pump cylinder elements disposed radially within said support, said support including depending feed portions each supporting a respective cylinder element and including a tapered 55 grease passageway to each cylinder element, each cylinder element including an inlet connected to the respective passageway, a piston in each cylinder element, and a centrally disposed actuating means for said pistons 60 mounted within the support between the depending feed portions. 65
- 65 6. In a lubricant dispensing device, a support, a grease reservoir mounted on said support, a plurality of depending discharge snouts formed in said support about the cen-

ter thereof and about the center of said reservoir, a pump located in the lower end of each snout, and means located centrally in the support for operating said pumps.

In witness whereof, I hereunto subscribe 70 my name.

CLYDE G. BUTLER.
